ATTORNEYS.

UNITED STATES PATENT OFFICE.

ARTHUR L. MYERS, OF LA CROSSE, WISCONSIN, ASSIGNOR TO NORTHERN ENGRAVING COMPANY, OF LA CROSSE, WISCONSIN, A CORPORATION OF WISCONSIN.

NAME PLATE.

Application filed March 28, 1927. Serial No. 178,825.

This invention relates particularly to means for securing name plates to automobile radiator shells, automobile lamp brackets, and the like, although not necessarily limited to that specific purpose.

The securing means is of a type in which the securing member proper is attached to the name plate and co-operates with the wall of the radiator shell, bracket or other part to which the name plate is to be secured.

An object of the invention is to provide means for securing a name plate to the part to which it is to be attached in an economical and effective manner.

15 A further object of the invention is to provide means for securing the name plate in position which will be of a character which will insure the name plate being properly positioned on the part to which it is attached.

20 Further objects of the invention will appear from the accompanying description, claims and statement of advantages.

In the accompanying drawings:

25 Fig. 1 is a front elevation of a portion of an automobile radiator showing the name plate applied thereto with my improved securing means.

Fig. 2 is a section on an enlarged scale on the line *a*—*a* of Fig. 1 showing the securing means before clinching.

30 Fig. 3 is a similar section showing the securing means clinched.

Fig. 4 is a front elevation of that portion of the radiator shell to which the name plate is applied.

35 Fig. 5 is a rear elevation of a portion of the name plate and its securing means.

Fig. 6 is a side elevation of a lamp bracket 40 showing a name plate of somewhat different form attached thereto with my improved securing means.

Fig. 7 is a rear elevation of a portion of the bracket showing the name plate applied thereto.

45 Fig. 8 is a rear elevation of a portion of the lamp bracket before the name plate has been attached.

Fig. 9 is a rear elevation of the form of name plate shown in Fig. 6.

50 Fig. 10 is a section on the line *b*—*b* of Fig. 9.

Referring first to Figs. 1 to 5 inclusive, 1 represents the shell of an automobile radiator 55 the forward side of which, just beneath the

filler opening, is provided with an opening 2 elongated preferably in a transverse direction and of trapezoidal form so that the opening at one end 2^a will be of greater height than at the other end 2^b.

The name plate shown in these figures consists of a disk 3 of comparatively thin metal having its edges crimped over a back plate 4 of heavier metal which has a slightly concavo-convex shape. This back plate 4 has a pair of prongs 5 and 6 which are formed integrally with the plate by cutting and bending first to the form shown in Fig. 2 and Fig. 5. These prongs are of different widths corresponding to the widths of the respective ends of the opening 2 so that the prongs can be inserted in the opening only when the name plate is right side up, thus insuring the proper positioning of the name plate on the shell.

The name plate is applied to the radiator shell before the parts of the radiator have been assembled by inserting the prongs into the opening and then clinching the free ends of the prongs against the rear wall of the shell as shown in Fig. 3, this clinching being accomplished by bending the inner or

free ends of the prongs in any suitable manner, but preferably by placing the radiator shell in a horizontal position on a substantial stand which has gauge pins for the shell so that the trapezoidal opening in the shell would come directly over an anvil or metal

85 form, then inserting the prongs of the name plate through the opening so that the prongs rest on the rounded portion of the anvil, and then giving the face of the plate a sharp rap with a mallet thereby causing the rear or free ends of the prongs to spread and clinch themselves to the rear wall of the shell. In Fig. 6 to Fig. 10 there is shown a name plate applied to the lamp bracket of an automobile by the same securing means.

The name plate proper is indicated at 7 and has a back plate 8 to which it is secured in any suitable manner. This back plate 8 has the same integral rearwardly extending prongs 9 and 10 formed by punching and bending the same from the plate itself.

The portion of the bracket to which the name plate is applied is indicated at 11 and is provided with the same kind of transverse elongated trapezoidally shaped opening 12 into which the prongs 9 and 10 are inserted and clinched in the manner before described.

By this arrangement a very simple and effective means is provided for securing a name plate in position on a radiator shell, lamp bracket or other part. All name plates of this character are provided with metallic back plates so that to form my securing means it is only necessary to strike the prongs from this back plate, form an opening in the part to which the name plate is to be applied and then 10 insert and clinch the prongs as described. Further, by making the respective places into which the prongs are inserted of greater height or width and forming the prongs of corresponding height or width, the proper 15 insertion of the name plate on the part to which it is applied is insured without any care upon the part of the workman.

Having thus described my invention, I claim:

- 20 1. In a securing device of the character described, a member, a structure to which said member is to be applied, and a pair of prongs of different dimensions in cross section projecting from said member, said structure being formed with apertured places corresponding respectively in dimensions to said prongs to receive said prongs, the free ends of said prongs after insertion into said apertured places being bent against the wall of said 25 structure to secure said member in position.
2. In a securing device of the character described, a member, a structure to which said member is to be applied, and a pair of integrally formed prongs cut and bent from said 30 member, said prongs being of different dimensions in cross section, said structure being formed with apertured places corresponding respectively in dimensions to said prongs to receive said prongs, the free ends of said 35 prongs after insertion into said apertured places being bent against the wall of said structure to secure said member in position.
- 40 3. In a securing device of the character described, a name plate, a back plate to which

said name plate is secured, a structure to which said plates are to be applied, and a pair of integrally formed prongs cut and bent from said back plate, said prongs being of different dimensions in cross-section, said structure being formed with apertured places corresponding respectively in dimensions to said prongs to receive said prongs, the free ends of said prongs after insertion into said apertured places being bent against the wall of said structure to secure said plates in position. 45 50 55

4. In a securing device of the character described, a member, a structure to which said member is to be applied, and a pair of prongs projecting from said member of different dimensions in cross section, said structure being formed with elongated opening of trapezoidal shape with the ends thereof corresponding in dimensions with the dimensions of said prongs, respectively, to receive said 60 65 prongs, the free ends of said prongs after insertion into said opening being bent against the wall of said structure to secure the wall of said member in position.

5. In a securing device of the character described, a name plate, a back plate to which said name plate is attached, a structure to which said plates are to be applied, and a pair of integral prongs cut and bent from said back plate, said prongs being of different dimensions in cross section, said structure being formed with an elongated opening of trapezoidal form with the ends thereof corresponding, respectively, in dimensions with the dimensions of said prongs to receive said prongs, the free ends of said prongs after insertion into said opening being bent against the wall of said structure to secure said plates in position. 70 75 80

In testimony whereof, I have hereunto set my hand this 10th day of March, 1927. 85

ARTHUR L. MYERS.
